LIGHT SOURCE

Heinrich Könemann, Munster, Germany

Application July 15, 1930, Serial No. 468,085
In Germany July 6, 1929

2 Claims. (Cl. 176—122)

The invention relates to a device for recording sound waves on a moving photo-sensitive support, using a tungsten arc lamp as the source of light for recording, and provides an arrangement enabling a clearer sound record to be obtained than heretofore.

The invention is based on the knowledge that the arc light of the tungsten arc lamp possesses not merely a high photo chemical activity, but has an extraordinary capacity for oscillating, and more particularly, is considerably freer from inertia than the remainder of the light emitted by the lamp, especially the light from the electrodes.

For these reasons, by the means given hereafter, the invention provides a way of eliminating the effect of factors which interfere with the character of the arc as a pure arc.

Two constructional examples of recording devices according to the invention are shown in the drawing, in which:

Figure 1 is a longitudinal section of a sound-current modulated tungsten arc lamp having a screened, pure arc, and

Figure 2 is a section through a recording apparatus having the means for screening the said arc situated in the optical arrangement.

It is well known to cause the light from a source of illumination to oscillate or fluctuate in rhythm with the sounds to be recorded, and to employ this light, by passage through a narrow aperture, to effect a photochemical change in the light-sensitive film which moves past the aperture. According to the present invention, it is proposed to employ a tungsten arc lamp, as a source of illumination. It has been found in practice that the records produced by such arc lamps are at times lacking in clearness, particularly with the higher frequencies of sound vibrations.

According to the present invention, a distinction is made between the several sources of light present in a tungsten arc lamp, to-wit: the electrodes and the arc itself. The electrodes are much slower in response to variations of current intensity by reason of inertia effects, as they are unable to become heated or to give off their heat at the necessary velocity. On the other hand, the arc itself responds much more quickly, and is employed according to the present invention as the actual source of illumination. For this purpose, a screen is provided to obstruct light rays from the electrodes and prevent them from falling upon the light-sensitive surface.

In Figure 1, 1 and 2 are the two tungsten electrodes of the recording lamp and 3 and 4 are the

currentleads and electrode holders mounted in the glass base 5 of the lamp, these parts being enclosed from the atmosphere by the glass envelope 6.

Screens 7 and 8, located on the leads or holders 3 and 4 of the electrodes 1 and 2, serve to allow only the arc light, coming from the arc itself and capable of rapid oscillation to issue from the vicinity of the arc and pass through the envelope 6. Thus, a bundle of light rays, representing only the arc light, passes toward the surface S which is to be illuminated, and may illuminate the same for the area indicated as L in Figure 1: while the light emitted by the electrodes of the recording lamp, and thus being less capable of oscillation by reason of the inertia referred to above, is cut off by the screens 7 and 8 from passage to the surface S, and may only pass outward from the arc lamp in the directions marked L1 and L2 in Figure 1.

The screens 7 and 8 may be combined to form a single, electrically non-conducting screen plate, which is provided with an aperture for the passage of the arc rays. Such a screen strengthens the two electrode holders 3, 4 in a very desirable manner and assists in maintaining the electrodes at a predetermined distance.

In the optical arrangement shown diagrammatically in Figure 2, the tungsten arc lamp employed is absolutely identical with that shown in Figure 1, except that the screens 7 and 8 are omitted, so that all the light of the tungsten arc lamp is emitted freely. The condenser 10 projects at the plane 12', 12' a complete image of the recording lamp; a screen 12, fixed at this point, allows however only the light of the arc, which is well capable of oscillating, to pass through the lens 11. The lens 11 therefore projects onto the film 14 at the point 15 an image of the light of the arc as it passes the narrow slot 13.

Instead of the method of screening shown, any other type of screening may be used, provided only that it is adapted to allow only the rays of light emitted by the arc, which is well capable of oscillating, to reach the photo-sensitive support.

In addition, the screening means serve to withhold other disturbing factors: wandering of the arc, uneven heating of the electrode ends, which disturb the homogeneity of the arc, and deviation of the arc from the most favourable shape for recording.

A chief means is to make the electrodes of such a shape that their ends which are directed

towards one another are each of the shape of a flat dome. Experiments have shown that by giving them this shape, the wandering of the arc and any uneven heating of the electrode ends 5 may be excluded.

It has also been found essential, in selecting the distance between the electrodes as well as the gas pressure prevailing in the lamp, to proceed from the point of view of obtaining a compact cylindrical shape of arc. If the arc becomes constricted, or if it becomes very wide at the cathode and very narrow at the anode, it loses recording power. The best distance between the electrodes for a maximum current strength of 10 1 to 2 amperes, is about 3 mm. The pressure is about 150 mm. of mercury. These, however, are not sharply defined optima; more particularly, one precaution (distance or pressure) may be replaced to some extent by the other.

20 In order to fix undisplaceably the most favourable distance between the electrodes, once it has been ascertained, the electrode holders or leads

3 and 4 are made of very robust dimensions. This obviates the danger of trembling of the electrode arms when the lamp receives shocks, which would disturb the distance between the electrodes and hence the continuity of the records.

80

I claim:

1. A source for producing rapidly varying degrees of illumination comprising a modulatable arc lamp having an enclosing envelop with electrode supports therein and tungsten electrodes on said supports, and screening means mounted on said supports within the envelop and in the path of the light emitted by the lamp for preventing the passage of light from the electrodes and permitting the passage of light from the arc 85 90 itself.

85

2. A source as in claim 1, in which the screening means includes non-conductive material connected to said supports whereby the screening means is mounted thereon without providing a 95 conductive path in shunt to said arc.
